UNITED STATES PATENT OFFICE.

ROY LEE CLEARY, OF KERLIN, ARKANSAS.

SHAVING COMBINATION.

Application filed August 16, 1927. Serial No. 213,370.

The present invention relates to an improved combination device for use by barbers and others in the art of shaving.

Briefly, the invention has reference to a 5 shaving brush, a razor, and a quick detachable connection between the brush and razor, whereby the brush may be mounted on the customary handle of the razor to facilitate shaving.

10 The particular details of construction, will become more readily apparent from the following description and drawings.

In the drawings:—

Figure 1 is an elevational and sectional 15 view of the combination device showing one embodiment of the razor, of the safety type.

Fig. 2 is a similar view showing a razor of the straight type.

Fig. 3 is a cross section on the line 3—3 20 of Fig. 1.

Fig. 4 is an enlarged fragmentary sectional view, showing a slightly modified form of the invention.

In Figs. 1 and 3, I have shown a safety 25 razor designated by the reference character 5, while in Figs. 2 and 4 I have shown a straight razor generally designated by the reference character 6. The safety razor 5 embodies the customary detachable handle 7 of cylindrical form.

The straight razor 6 embodies the customary sheath or shield type of handle 8 into which the blade 9 is foldable. Associated with the razor handle in either instance, is an attachment generally designated by the reference character 9. The attachment comprises a bristle brush 10, a head 11, and a resilient clamping device 12. The device 12 comprises a plurality of circumferentially spaced resilient main fingers 13 carrying 40 auxiliary fingers 14.

The upper ends of the fingers 13 are flared outwardly to facilitate attachment while the free end portions of the smaller fingers 14 45 are directed outwardly to insure maintenance of grip.

It will be seen that in both forms of the invention we have a separable brush attachment, capable of being readily applied to the 50 handle of a razor, so that the razor handle has a double function forming a handle for

a shaving brush and a manipulating handle for the razor.

It is thought that this combination of devices provides a composite device, which is 55 more easily handled in less time and with less labor. It is believed that a device of this type is particularly advantageous and efficient for use by barbers and in the home.

The only distinction between the arrangement shown in Fig. 4, is that the supplemental fingers 14 are omitted, for simplicity.

It is thought that by considering the description in connection with the drawings, a clear understanding of the invention will 65 be had. Therefore, a more lengthy description is thought unnecessary.

Minor changes in shape, size, and re-arrangement coming within the field of invention claimed, may be resorted to if desired. 70

Having thus described my invention, what I claim is new is:—

1. In a shaving appliance of the class described, in combination, a razor including a handle, a shaving brush including a bristle 75 backing, a head, said head having a depression for reception of said handle, and a clamping means carried by said head and detachably connected with said handle.

2. In a structure of the class described, in combination, a razor including a handle, a bristle brush, a head carried thereby, said head having a depression for reception of said handle, and a multiplicity of spring clamping fingers carried by said head, said 85 fingers being arranged in circumferentially spaced relation, and disposed in sets of two, there being main outer fingers and supplemental inner fingers carried by the outer fingers. 90

3. As a new product of manufacture, an attachment for a razor handle comprising a bristle brush having a depression for reception at the end of the razor handle, and a multiplicity of circumferentially spaced 95 pairs of fingers, each pair embodying a main outer finger having a flared free extremity, and an inner finger having a flared extremity.

In testimony whereof I affix my signature.

ROY LEE CLEARY.
